(57) **CLAIM**

The ornamental design for a dual paint roller, as shown and described.

DESCRIPTION

FIG. 1 is a top, front and right side perspective view of a dual paint roller embodying my new design, wherein exemplary rollers are shown in phantom;

FIG. 2 is a top plan view thereof;

FIG. 3 is a left side elevational view thereof, the right side elevational view being a mirror image;

FIG. 4 is a bottom plan view thereof;

FIG. 5 is a front elevational view thereof; and,

FIG. 6 is a rear elevational view thereof.

The broken lines shown in FIG. 1 form no part of the claimed design.

1 Claim, 3 Drawing Sheets

FIG. 1

FIG. 2

FIG. 3
